UNITED STATES PATENT OFFICE.

SIMON G. PETTERSON AND BERTILL CARL PETTERSON, OF PINE BLUFF, ARKANSAS.

TOY WAGON.

1,328,760.

Specification of Letters Patent. Patented Jan. 20, 1920.

Application filed February 15, 1919. Serial No. 277,158.

To all whom it may concern:

Be it known that we, SIMON G. PETTERSON and BERTILL C. PETTERSON, citizens of the United States, and residents of Pine Bluff, 5 in the county of Jefferson and State of Arkansas, have invented certain new and useful Improvements in Toy Wagons, of which the following is a specification.

Our invention is an improvement in toy wagons, and has for its object to provide a wagon of the character specified, wherein the wagon is provided with movable figures whose movement is controlled by the movement of the wagon.

15 In the drawings:

Figure 1 is a perspective view of the wagon in use;

Fig. 2 is a side view;

Fig. 3 is a section on the line 3—3 of Fig. 20 2, looking in the direction of the arrows adjacent to the line;

Fig. 4 is a partial side view of a modified construction;

Fig. 5 is a section on the line 5—5 of Fig. 25 4, looking in the direction of the arrows adjacent to the line;

Fig. 6 is a partial side view of another embodiment of the invention.

In the embodiment of the invention shown 30 in Figs. 1 to 3, inclusive, the improved wagon comprises a plate or platform 1 having front and rear bolsters 2 and 3, on which are journaled axles 4 and 5, respectively, and wheels 6 and 7 are mounted on the axles.

35 The wheel 6 is journaled between the bolsters 2 and the said bolsters extend longitudinally of the plate, while the bolster 3 is journaled transversely of the plate. The shaft 5 is a crank shaft, as shown, and guide 40 rails 8 and 9 are secured to the upper face of the platform extending longitudinally thereof, and spaced apart from each other to form guideways extending parallel with the long axis of the plate.

45 Wheels 10 are mounted to move in the guideways, and a figure 11 is supported by each slide, the figures in the present instance being the representations of geese. Links 12 connect the respective blocks with the 50 cranks of the crank shaft, and it will be evident that when the crank shaft is rotated the slide blocks will be reciprocated in the guideways, and since the cranks of the crank shaft are oppositely arranged the slides will 55 be reciprocated in opposite directions.

A third figure 3 is mounted at the front of

the plate, the said figure being in the present instance the representation of a man, and the said figure faces the figures 11, so that the said figures move toward and from the 60 figure 12. An eye 14 is provided at the front of the wagon to which may be attached a cord 15 for drawing the wagon.

In the embodiment of the invention shown in Figs. 4 and 5, the plate 16 is supported 65 by the front wheel (not shown) and the rear wheels 17 which are secured to the crank shaft 18 journaled on the bolster 19. The guideways 20 are arranged longitudinally of the platform or plate, forming the guideways within which are slidable the slides 21.

A figure 22 is provided, the said figure having jointed arms and legs, and the legs are connected with the slides as shown in Fig. 3, the foot portion of each leg being 75 secured to a slide. Links 23 connect the respective slides with the crank shaft, and it will be obvious that when the shaft is rotated the legs of the figures will be advanced and retracted to simulate walking.

In the embodiment of the invention shown in Fig. 6 the legs of the figure 24 are connected by links 25 with the arms, in such manner that when the blocks 26 are reciprocated by the links 27 connected to the crank 85 shaft 28, both arms and legs of the figure will be reciprocated. The crank shaft is supported by the bolster 29 which is connected with the wagon body 30.

In each embodiment of the invention there 90 is provided a wagon body having at one end a crank shaft to which the supporting wheels are secured, and having guideways in which are movable slides, the said slides being connected to the crank shaft to be reciprocated in opposite directions, and the slides support a figure or figures and impart rotation thereto when they are reciprocated.

We claim:

1. A wagon of the character specified, comprising a wagon body, wheels for supporting the body, a crank shaft having cranks and journaled at one end of the body to which the wheels at the said end are secured, said body having on the upper face thereof a plurality of guideways, a slide movable in each guideway, a connection between each slide and a crank of the shaft, the cranks being oppositely arranged to reciprocate the slides in opposite directions, and figures supported by the slides, said fig-

ures comprising representations, one of said figures being connected to each slide.

2. A wagon of the character specified, comprising a wagon body, wheels for supporting the body, a crank shaft having cranks and journaled at one end of the body to which the wheels at the said end are secured, said body having on the upper face thereof a plurality of guideways, a slide 5 movable in each guideway, a connection between each slide and a crank of the shaft, the cranks being oppositely arranged to reciprocate the slides in opposite directions, and figures supported by the slides, the legs 10 of the said figures being connected to the slides to simulate walking.
3. A wagon of the character specified, comprising a wagon body, wheels for supporting the body, a crank shaft having 15 cranks and shafts journaled at one end

of the body to which the wheels at the said end are secured, said body having on the upper face thereof a plurality of guideways, a slide movable in each guideway, a connection between each slide and a crank 25 of the shaft, the cranks being oppositely arranged to reciprocate the slides in opposite directions, and figures supported by the slides.

4. In combination, a wheel supported 30 body, a crank shaft having cranks and driven by the movement of the body, said body having guideways, slides movable in the guideways, connections between the slides and the crank of the shaft for reciprocating the slides when the crank shaft is rotated, and figures supported by the slides.

SIMON G. PETTERSON,
BERTILL CARL PETTERSON.
